CONTROL FOR POWER-OPERATED
AIRCRAFT GUNS

Evelyn Cecil Muschamp d'Assis-Fonseca, Bristol, England, assignor to The Bristol Aeroplane Company Limited, Bristol, England, a British company

Application May 23, 1945, Serial No. 595,403
In Great Britain September 2, 1943

Section 1, Public Law 690, August 8, 1946
Patent expires September 2, 1963

5 Claims. (Cl. 89—134)

1

This invention concerns guns for aircraft. Usually the gun is rotatable about one axis to give the gun traverse and it also rotatable about a second axis to elevate or depress the gun, and the gun is fired by a power-relay controlled by the gunner. Hereinafter it will be assumed that the traverse of the gun takes place about a vertical axis and that the elevation of the gun occurs about a horizontal axis but it will be understood that the guns can be mounted, or can assume in use, any other position, and the expression "field of fire" will be used to mean the field covered by the full range of both traverse and elevation.

In guns of this kind, the gun has a wide field of fire and generally can be trained on a target by any of a number of different combinations of traverse and elevation. It may happen that when the gun is trained in certain directions within the field of fire it is not safe to fire the gun because some part of the aircraft lies in the direction of fire. The object of this invention is to provide improved means for automatically preventing the gun being fired when it is so trained.

According to the present invention guns of the above kind are capable of being traversed and/or elevated at more than one speed, and the size of the field of fire within which the gun is prevented from firing is automatically varied to suit the prevailing conditions of said speed.

According to another feature of the invention the size of the initial or basic field of fire within which the gun is prevented from firing is automatically enlarged as the speed of traverse and/or elevation is increased, said enlargement to the initial size of said field taking place only on the side thereof which the gun first approaches.

When an electrical system of control is used for this purpose, it comprises a conducting plate, which represents the field of fire, a contact movable over it in accordance with the training movements of the gun, and insulated areas on the plate which represent the regions in which the firing is not safe, and the circuit through the contact member is interrupted by the insulation to prevent firing. When the present invention is applied to such a system, the effective point of engagement of the contact with the plate is varied according to the rate of the training movements, and this may be accomplished by using auxiliary contacts, or by imparting additional movement to the contact, as hereinafter described.

2

A specific embodiment of the invention will now be described by way of example with reference to the accompanying drawings of which:

Figure 1 is a diagrammatic perspective view showing part of a mechanism in accordance with the present invention for automatically stopping the firing of a gun when the latter is trained in certain directions and an electrical circuit associated with said mechanism,

10 Figure 2 is a sectional elevation of mechanism in accordance with the present invention, and

Figure 3 is a schematic front view of a gun turret for an aeroplane incorporating the mechanism of Figure 1.

15 The mechanism for automatically preventing firing is associated with guns 50 mounted in a turret 51 in which the traverse of the guns is produced solely by the rotation of the turret about a vertical axis. The turret comprises a transparent dome 52 in which the guns are mounted with the breech and actuating mechanism within the dome and the barrels extending through the dome. The guns 50 are suitably

20 carried by the turret 51 so as to be rotatable therewith and are supported upon a structure so as to be capable of elevation and depression.

The part of the turret already described extends above the fuselage 53 of the aircraft and has a skirt depending from it through a suitable opening into the fuselage. A suitable bearing is provided to support the turret where it enters the fuselage, for complete rotation.

25 The lower part 54 of the turret comprises a platform, a gunner's seat carried thereby, ammunition boxes, and containers for spent ammunition, all of which are rotated with the turret as the guns are traversed.

The mechanism for rotating the turret and elevating the guns comprises a separate electric motor 55, 56 for each movement. The traversing motor 55 will drive, through reduction gearing, a gear wheel 57 meshing with a fixed gear ring 58 secured to the part 54 of the turret. The elevating motor 56 will drive through reduction gearing, an elevating screw 59 co-operating with a nut 58 carried by the gun supports 59.

30 The gunner's sighting apparatus is arranged in the upper part of the turret between the guns so as to be convenient to the gunner as is also a control handle 62 by which the rotation of the turret and the elevation and firing of the guns is controlled. The firing is electrically controlled by a switch which upon being closed by the gunner completes a circuit to energise a solenoid.

The latter is then effective to bring the firing mechanism into operation.

Associated with each gun in the turret is the cutout mechanism diagrammatically shown in Figure 1 of the accompanying drawings.

Referring to Figure 1 the fixed gear ring mentioned above is adapted to rotate a cylinder 10 through suitable gearing. The cylinder is also adapted to be raised and lowered with the movements of elevation and depression of the gun so that said cylinder rises or falls as the guns are elevated or depressed and also rotates as the guns are traversed with rotation of the turret. The cylinder is of electrically conducting material and has inserted in its face a number of non-conducting elements 11, 11a (hereinafter referred to as "images") each of which is an image of a zone or field of fire in which it is unsafe to fire the guns.

Co-operating with the image-cylinder 10 are a set of three electrical brushes 12, 13 and 14 the central brush 13 of which is connected with a firing switch 15 whilst the pair of lateral brushes 12, 14 are respectively connected to two poles 16, 17 of a selector switch 18. The latter is under the control of the traversing control handle and is so arranged that immediately upon said handle being moved to rotate the turret in one direction the selector switch 18 is closed to complete one circuit and upon the handle being set to produce a traverse in the other direction the selector switch is closed to complete another circuit. The circuit in each case comprises the firing switch 15, the central brush 13, the conducting image-cylinder 10, a lateral brush 12 or 14, the selector switch 18, a firing solenoid 19 and a battery 20. The firing of the guns is electrically controlled by the switch 15 which upon being closed by the gunner completes one or other of the circuits to the solenoid 19. The latter is then effective to bring the firing mechanism into operation.

The selector switch 18 is also connected to one side of a switch 21 which is normally closed. The other side of the switch 21 is connected with the image-cylinder 10 by way of conductor 22 and brush 24 so that whilst said switch is closed a circuit is completed from the cylinder to the switch 21, the selector switch 18, the firing solenoid 19, and then by the battery 20 to the firing switch 15, the central brush 13 and the cylinder 10.

The switch 21 is under the control of a governor 23 which is driven by the traversing motor 55 through gears 57, 60 (Figure 1) and is so adjusted that whilst the rate of traverse remains below a predetermined value (the "slow-rate" of traverse hereinafter referred to) the governor switch 21 is closed. However when the rate of traverse is raised above said predetermined value (the "high-rate" of traverse) the switch 21 is open.

The operation of the interrupter mechanism described and the conditions under which an enlargement of the unsafe field of fire should be provided for now follows:

Let it be assumed that the guns are stationary and are pointed in a direction in which it is safe to fire. When the firing switch 15 is closed a circuit is completed from the battery 20, the firing solenoid 19, the governor switch 21, conductor 22, brushes 24 and 13, switch 15 and so back to the battery. Upon the solenoid 19 being thus energised the gun will commence to fire.

Under these circumstances (when no traverse

of the gun is taking place) the selector switch 18 is open so that neither of the circuits leading from the lateral brushes 12, 14 to the firing solenoid 19 are completed.

Whilst the gun is thus being fired let it be assumed that the traversing control handle is actuated so as to produce rotation of the turret at a slow-rate towards a zone in which it is unsafe to continue firing the gun. As the turret is rotated the image-cylinder 10 will also be rotated for example in the direction indicated by arrow A in Figure 1. The actuation of the traversing control handle adjusts the selector-switch 18 on to the contact 17 for the contact 14 which is the leading contact of the three 12, 13, 14 in respect of the movement of the image-cylinder 10 across them. At the instant at which the gun reaches the unsafe zone of fire, the image 11a on the cylinder engages with the central conductor 13.

Prior to this engagement, the lateral brush 14 has been engaged by the image 11a and the circuit from said brush to the firing solenoid 19 which was completed by the closing of the selector switch 18 on contact 17 when the traversing control handle was actuated, is broken. The breaking of this circuit has no effect however, since the circuit to the firing solenoid 19 through the central brush 13, contact 24 and governor-switch 21 remains effective. The gun will therefore continue firing until such time as the image 11a engages with the central brush 13 whereupon the circuit to the firing solenoid 19 is interrupted and firing ceases. This occurs at the instant at which the gun is immediately within the unsafe firing zone.

If the turret continues to be traversed in the same direction the image 11a will move across the central brush whereupon two circuits are simultaneously completed: the one circuit comprises central brush 13, image-cylinder 10, brush 24, and governor-switch 21 and the other circuit comprises central brush 13, lateral brush 14 and selector switch 18. Each such circuit includes firing solenoid 19 so that upon brush 13 leaving image 11a firing re-commences.

Each image 11, 11a is so constructed and dimensioned that whilst the turret is being rotated at the slow-rate, it is impossible for the gun to fire so as to hit an object within the unsafe zone of fire although in certain circumstances they may fire within this zone. For instance, if at the instant the firing circuit is interrupted the striker pins of the guns are about to engage the primers of the bullets then these shots will be fired within the unsafe zone of fire. It is only necessary, however, to make the image of such a size that under these or similar circumstances the bullets cannot hit an object within the unsafe zone of fire. Whether this will happen however, is dependent upon the rate of traverse. As this is increased it is necessary to make the image larger. Accordingly in gun turrets having a low and a high rate of traverse it is necessary to ensure, on the one hand, that the firing circuit is interrupted at all times as late as is possible so that the field of fire is as great as possible, and on the other hand, that such interruption takes place earlier with a high rate of traverse than with a low rate of traverse.

In the construction described with reference to Figure 1 the governor-switch 21 is set to open when the high-rate of traverse comes into being. Accordingly the firing circuit cannot be completed through the contact 24 but only through

the central brush 13, the image-cylinder 10, the leading brush of the two lateral brushes 12, 14, the selector-switch 18, the firing solenoid 19, battery 20 and firing switch 15. This circuit is broken when a lateral brush is engaged by the image. The firing circuit is thus interrupted earlier in point of time than when the low-rate of traverse is operative by an amount which is equivalent to the time taken by the image-cylinder to move at the high-rate of traverse through the angular distance between the central and lateral brushes.

It will be appreciated that the particular circumstances described above of being able to fire within an unsafe zone although the firing circuit is broken, does not occur when the gun is moved out of the unsafe zone into a safe field of fire. Accordingly it is desirable that the gun immediately commences to operate when the fringe of the field of fire is reached and that no lapse of time in doing so occurs. This will occur provided that the firing circuit is completed immediately the central brush leaves the image and engages the conducting image-cylinder 10. Since the lateral brush through which the firing circuit is completed at high-rates of traverse is in advance of the central brush, it both engages and leaves the image before the central brush and firing will take place as soon as the central brush 13 leaves the image.

It will be appreciated that when the turret is rotated in the opposite direction to that referred to above, the image-cylinder 10 will rotate in the opposite direction to the arrow A. At the same time the selector-switch 18 will engage the contact 16 so that the image 11 will be brought into engagement with the lateral brush 12 before engaging the central brush 13.

In Figure 1 the chain dotted image 11b represents the enlarged field of unsafe fire due to increase in the speed at which the gun is trained upon a target. The enlargement to the right hand side of the image 11a so as to produce image 11b is effected when the image cylinder 10 rotates in the direction of arrow A and when the firing circuit is completed through brushes 13 and 14. Similarly the enlargement on the left hand side of the image 11a to produce the image 11b is effected when the image cylinder 10 is rotated in the opposite direction to arrow A and when the firing circuit is completed through brushes 12 and 13. Similar considerations apply to the lower image 11 shown on the cylinder.

A practical embodiment of the mechanism of Figure 1 is shown in Figure 2. This construction is adapted for use in a gun turret part of which is generally indicated by the reference numeral 40 having a pair of spaced parallel guns one of which is indicated at 41. With such a twin gun installation it is necessary to provide mechanism for individually controlling the firing of each gun so that it does not fire within the unsafe zone. In the construction shown the fixed gear ring of the turret referred to above is indicated at 25 whilst the turret support bearing is shown at 42. Engaging with said gear ring is a gear 26 so that upon rotation of the turret relative to the fixed gear ring 25 the gear 26 is rotated and transmits to the image-cylinder 10 through gears 27, 28. The image-cylinder 10 is carried upon a central tube 29 which is supported at its lower end in a bearing 30 and at its upper end by bearing 31. The gun is pivotally mounted as at 32 and is connected with rod 35 by means of a link 33 and arm 34. The rod 35

is received by a socket 43 having a transverse pin 44 which passes through slots 45 in tube 29 and is attached to cap 46 carried by the cylinder 10 so that the gun and cylinder are raised and lowered together. The image-cylinder 10 is divided into an upper and lower portion, the upper portion of which carries the images 11 which are associated with one gun whilst the lower portion carries the images associated with the other gun. Both parts of the cylinder are provided with the brushes 12, 13, 14 and 24 described with reference to Figure 1. The brushes associated with the upper part of the cylinder are spaced apart from the brushes associated with the lower part of the cylinder by an amount slightly greater than half the depth of the image-cylinder 10. Both sets of brushes are secured to a carrier 36 which surrounds the image-cylinder 10 and is supported by the gun turret structure. The operation of the upper and lower part of the mechanism in stopping and starting the firing of its associated gun is as described with reference to Figure 1.

I claim:

- 25 1. A gun installation comprising a gun, driving means for training the gun on to a target at more than one speed, a control for regulating the driving means, a conducting plate representing the total field of fire of the gun, a central 30 and a pair of lateral contacts disposed one on each side of the central contact said contacts being simultaneously, relatively movable over the conducting plate to reproduce the training movements of the gun, an insulated area on the plate 35 representing the unsafe field of fire of the gun, a switch movable into series with either lateral brush and actuated by the control for the gun-training means, a switch in series with the central contact, a governor driven by the gun-training means and adjusting the central-contact switch, a firing circuit being completed through the central and a lateral brush, the central-contact switch being opened by said governor when the gun-training means moves the gun at a predetermined speed.
- 40 2. A gun installation as claimed in claim 1 wherein the conducting plate is constituted by a cylinder which is rotated with traverse of the gun and raised and lowered with movements of 45 elevation of the gun.
- 50 3. A gun installation comprising a gun, power means for training the gun on to a target at more than one speed, an electric circuit for controlling the firing of the gun, an interrupter mechanism forming part of said circuit to stop the gun firing when the latter is aimed to within a predetermined unsafe field of fire when being trained at a normal speed, means responsive to the speed at which the gun is trained on to the 55 target and a switch mechanism forming part of the interrupter mechanism said switch mechanism being actuated by said speed-responsive means automatically to interrupt the firing of the gun before the latter is aimed to within the unsafe field of fire with increase in the speed at which the gun is trained beyond said normal speed.
- 60 4. A gun installation comprising a gun, power means for training the gun on to a target at more than one speed, an electric circuit for controlling the firing of the gun, an interrupter mechanism forming part of said circuit to stop the gun firing when the latter is aimed to within a predetermined unsafe field of fire, means responsive to the speed at which the gun is trained 65

on to the target, a switch mechanism forming part of the interrupter mechanism said switch mechanism being actuated by said speed-responsive means, automatically to interrupt the firing of the gun before the latter is within the unsafe field of fire with increase in the speed at which the gun is trained beyond said normal speed and a selector switch in the circuit of said switch mechanism said selector switch being actuated by the gun-training means to arrange the switch mechanism so that the automatic earlier interruption of the firing circuit occurs only on the side of the unsafe field of fire which the gun first approaches.

5. A gun installation comprising a gun, power means for training the gun on to a target at more than one speed, an electric circuit for controlling the firing of the gun, a conducting plate forming a part of said circuit and representing the total field of fire of the gun, a contact relatively movable over the conducting plate to reproduce the training movement of the gun, an insulated area on the plate representing the un-

safe field of fire of the gun, means responsive to the speed at which the gun is trained on to the target said speed-responsive means actuating said contact to vary the instant of engagement of the contact with the insulated area so as to increase the unsafe field of fire of the gun with increase in the speed at which the gun is trained.
